LOOSE LEAF BINDER

Filed Nov. 4, 1929

UNITED STATES PATENT OFFICE

ADOLPH G. LOTTER, OF MILWAUKEE, WISCONSIN, ASSIGNOR TO STATIONERS LOOSE LEAF CO., OF MILWAUKEE, WISCONSIN, A CORPORATION OF WISCONSIN

LOOSE LEAF BINDER

Application filed November 4, 1929. Serial No. 404,678.

This invention relates to certain new and useful improvements in loose leaf binders particularly of the type having two binder heads, from one of which flexible posts or chains are extensible to have their outer free ends readily detachably fixed to the other head so that upon the operation of suitable take-up mechanism, a retaining pressure is applied to a body of leaves inserted between the binder heads.

Various methods have been used in the past for connecting the detachable binder head with the post members, one of which is shown in my copending application, Serial No. 282, 15 725, filed June 4, 1928. However, with this method the slide bar which forms the means for connecting the detachable binder head with the post members was apt to be accidentally withdrawn permitting the detachment of the head from the post members and the consequent displacement of the leaves.

It is, therefore, one of the objects of this invention to provide an improved cooperating connection between the post members and the 25 slide bar which positively prevents movement of the bar when the post sections are drawn taut.

A more specific object of this invention resides in the provision of depressions formed 30 in the slide bar adjacent the key hole slots which receive the ends of the post members, and in which the post member ends are disposed when drawn taut to thus positively lock the bar against longitudinal movement.

With the above and other objects in view 35 which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have 45 illustrated one complete example of the physical embodiment of my invention constructed according to the best mode I have so far devised for the practical application of the principles thereof, and in which:

Figure 1 is a top view of a portion of a loose leaf binder constructed in accordance with my invention and having a portion of the upper binder head broken away to illustrate structural details;

Figure 2 is a rear view of the binder with portions broken away and in section; and

Figure 3 is a fragmentary, detail view similar to Figure 2, illustrating the position of the parts when the post members are extended and the slide is withdrawn to permit detachment of the upper binder head.

Referring now more particularly to the accompanying drawings, the numerals 5 and 6 represent upper and lower binder heads, respectively, of a loose leaf binder between which a body of leaves 7 is adapted to be clamped, covers 8 (but one being shown) hingedly connected with the binder heads, protecting the leaves. The binder heads are connected by flexible post members 9 whose inner ends are received within the lower head 6 and whose outer ends are extensibly projected therefrom to be engaged with the upper head. As is customary, the innermost ends of the flexible post members are connected with suitable take-up mechanism, indicated as 9a, and which is of the construction shown in detail in U. S. Patent No. 1,184,979 of May 30th, 1916, to effect the extension and retraction of the post members upon actuation of a key 10.

Both binder heads are of tubular construction and are preferably formed of similar channel members 11 arranged with their edges abutting. The particular construction of the lower binder head, however, forms no part of this invention and, therefore, the following description will be directed specifically to the upper binder head 5.

The upper and lower walls of the upper head which are formed by the webs of the channel sections 11, are provided with aligned apertures 12 and 13, respectively, adjacent each end. The apertures 13 being in the bottom wall are adapted to receive the adjacent outermost ends 14 of the flexible post members to permit their extension into the interior of the upper binder head and the apertures 12 serve to locate cup-shaped sock-

et members 15. The bottoms of the members 15 form substantially a continuation of the outer surface of the binder head and annular flanges 16 formed on the members and lying directly against the under-side of the upper wall are riveted thereto, as at 17, to secure the cup-shaped members in position.

The outer ends of the flexible post members are annularly grooved, as at 18, to provide means for engaging a slide bar 19 to connect the flexible post members with the upper binder head. The slide bar 19 extends throughout substantially the entire length of the upper binder head and is longitudinally 15 slidable therein, being spaced from the lower wall by downwardly struck depressions 20 adjacent each opening 13. Guides or feet 21 riveted or otherwise secured to the slide bar cooperate with the depressions 20 to maintain the bar spaced from the lower wall and a spring 22 riveted to the bar yieldably engages the upper wall and thus holds the bar against vertical movement.

Adjacent each depression 20 the bar is provided with a key-hole slot 23 whose enlarged portions 24 align with the socket members 15 and consequently the ends of the flexible post members when the bar is withdrawn, as illustrated in Figure 3.

30 A hook portion 25 formed on one end of the bar which extends through an opening 26 in the adjacent end of the binder head, provides means for moving the bar from one position to another. With the bar withdrawn, as illustrated in Figure 3, it is readily apparent that the binder head may be assembled with the ends of the flexible binder post members, providing the post are sufficiently loose. In this position the ends 14 of the 40 flexible posts are received wholly within the socket members 15 so that the posts are rigidly held during the inward movement of the slide bar 19 to engage the reduced portions 27 of its key hole slots 23 with the annular 45 grooves 18 of the post members to connect the binder head with the post members.

It is noted that the ends of the reduced portions 27 of the key-hole slots are in line with the center of the depressions 20 so that 50 as the post members are drawn taut, the outer ends 14 thereof bind against the outer surface of the slide bar within the depressions 20 so that longitudinal movement of the bar is positively prevented except when the post sections are sufficiently extended. From this it is obvious that after the upper 55 binder head is assembled with the post members, accidental movement of the slide bar and the consequent detachment of the binder head is impossible.

It is also apparent that the depressions 20 will at all times insure the complete inward movement of the slide bar, for if the operator should neglect to move the bar to its fully 60 inserted position, the application of tension

to the flexible post members in acting upon the sides of the depressions automatically moves the bar to its proper operative position.

What I claim as my invention is:

1. In a loose leaf binder, a pair of binder heads, a post member having extensible connection to one head and adapted to be passed into the other, means for applying tension to said post member, a slide bar concealed within said other binder head for readily detachably connecting the same with the post member, and means for positively preventing detachment of the slide bar from the post member when tension is applied to the post member. 70

2. In a loose leaf binder, a pair of binder heads adapted to clamp a body of leaves therebetween, an extensible post member carried by one binder head and adapted to be passed through the body of leaves and into the other binder head, means for retracting said post member, a slide bar within said other binder head adapted to be detachably connected with the end of the post member upon longitudinal movement of the slide bar, and means carried by the slide bar for preventing longitudinal movement thereof when the post member is retracted. 85

3. In a loose leaf binder, a pair of binder heads, a substantially flexible post member having extensible connection with one binder head and adapted to be passed through a body of leaves and into the other binder head, means for readily detachably connecting said other binder head with the end of the flexible post member, means for drawing said post member taut when connected with said other binder head to clamp a body of leaves between the two binder heads, and means positively preventing detachment of the said other binder head from the end of the flexible post member when the post member is drawn taut to clamp a body of leaves. 95

4. In a loose leaf binder, a pair of binder heads, a substantially flexible post member having extensible connection with one head and adapted to be passed through a body of leaves and into the other head, means for applying tension to said post member, a slide bar within said other head and having means detachably connectible with the end of the post member to readily detachably connect the said other binder head with the post member, whereby the application of tension to the post member clamps a body of leaves therebetween, and an abutment on said slide bar cooperating with said post member for preventing its detachment from the end of the flexible post member while the post member is under tension. 110

5. In a loose leaf binder having a flexible, extensible post member and a removable binder head, means for readily detachably connecting the post member with the binder 120 130

head said means including a slide bar mounted within the binder head and having a readily detachable interlocking engagement with the post member upon longitudinal movement of the slide bar, and an abutment carried by the slide bar for preventing its accidental detachment from the post member.

5 6. In a loose leaf binder, a pair of binder heads between which a body of leaves is adapted to be clamped, a substantially flexible post member having extensible connection with one binder head and adapted to be passed through a body of leaves and into the other head, a slide bar within said other binder head having a key-hole slot with which the end of the post member is engageable to readily detachably connect said other binder head with the post member upon longitudinal movement of the slide bar, means for placing said post member under tension, and means formed on the slide bar adjacent the key-hole slot for preventing longitudinal movement of the slide bar and its consequent detachment from the post member when the 25 post member is under tension to clamp a body of leaves.

7. In a loose leaf binder, a pair of binder heads, substantially flexible post members, means for applying tension to said post members to draw the post members into one binder head, a slide bar longitudinally movable within the other binder head and adapted for detachable connection with the free ends of the post members before tension is applied to the post members, and means positively preventing detachment of the slide bar from the post members when the post members are in tension.

8. In a loose leaf binder, a pair of binder heads between which a body of leaves is adapted to be clamped, a substantially flexible post member carried by one binder head and adapted to be passed through a body of leaves and into the other binder head, means for applying tension to said post member, guide means within said other binder head for receiving the outermost end of the flexible post member and holding it against all but longitudinal movement with respect to the axis of the post member, a slide bar within said other binder head, cooperating means carried by the slide bar and the post member end for effecting a readily detachable connection therebetween upon longitudinal movement of the slide bar, said guide means holding the post member end during longitudinal movement of the slide bar, and means for preventing detachment of the slide bar from the post member end when the post member is under tension to clamp leaves between the binder heads.

9. In a loose leaf binder having a pair of binder heads, substantially flexible post members carried by one head, means for drawing the post members into said binder head, a

slide bar within the other binder head and movable longitudinally thereof to readily detachably connect said other binder head with the free ends of the post members, and means whereby longitudinal movement of the slide bar to release the said other binder head imparts outward longitudinal movement to the post members whereby the slide bar is held against such movement when the post members are under tension.

10 In testimony whereof I have hereunto affixed my signature.

ADOLPH G. LOTTER.
